(57) **CLAIM**

The ornamental design for an electron microscope, as shown and described.

DESCRIPTION

FIG. 1 is a forward perspective view of an electron microscope showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a cross-sectional view thereof taken along line A-A in FIG. 2;

FIG. 9 is an enlarged view thereof showing details enclosed by lines B-B and C-C in FIG. 8; and,

FIG. 10 is another front view thereof.

Portions of the electron microscope shown in dashed lines in FIGS. 1-10 depict unclaimed portions of the electron microscope that are included for environmental purposes only. The broken lines with long dashes in FIG. 9 are for illustrative purposes showing boundaries of the enlarged view of FIG. 9 and form no part of the claimed design.

The broken lines in FIG. 10 depict a Light Emitting Diode (LED) of the electron microscope and form no part of the claimed design.
